CLAIM

The ornamental design for a bottle stopper as shown and described.

DESCRIPTION

FIG. 1 is a top plan view of a bottle stopper showing my design;

FIG. 2 is a front elevation view thereof;

FIG. 3 is a left elevation view thereof;

FIG. 4 is a right elevation view thereof;

FIG. 5 is a bottom plan view thereof;

FIG. 6 is a rear elevation view thereof;

FIG. 7 is an exploded perspective view thereof shown with the O-rings removed and relocated below the rest of stopper for the purpose of clarity;

FIG. 8 is a top-front perspective view thereof; and,

FIG. 9 is a bottom-rear perspective view thereof.

1 Claim, 2 Drawing Sheets
